United States Patent Office

Des. 224,579

Patented Aug. 1, 1972

224,579

TIRE

Richard J. Skerl, Barberton, Ohio, assignor to The B. F. Goodrich Company, New York, N.Y.

Filed Nov. 18, 1971, Ser. No. 200,264

Term of patent 14 years

Int. Cl. D12—15

U.S. Cl. D90—20

The figure is a perspective view of a tire showing my new design.

It is to be understood that the tread pattern continues as shown throughout the circumference of the tire, and the tread shoulder on the side opposite the portion shown is a mirror image thereof.

The characteristic features of the design reside in tread and tread shoulder portions of the tire.

I claim:

The ornamental design for a tire, substantially as shown and described.
